DESIGN FOR A JUG

Arthur Junior Calpha, Winchester, Ind., assignor
to Olean Glass Company, Olean, N. Y., a cor-
poration of New York

Application October 8, 1934, Serial No. 53,517

Term of patent 14 years

To all whom it may concern:

Be it known that I, Arthur Junior Calpha, a citizen of the United States, and residing at Winchester, in the county of Randolph, and State of Indiana, U. S. A., have invented a new, original, and ornamental Design for a Jug, of which the following is a specification, reference being had to the accompanying drawings, forming a part thereof, wherein:

Figure 1 is a view in side elevation of a jug illustrating my design;

Fig. 2 is a view in end elevation of the jug shown in Fig. 1; and

Fig. 3 is a sectional view of reduced size taken on line III—III of Fig. 1 in horizontal section of my jug.

I claim:

The ornamental design for a jug substantially as shown.

ARTHUR JUNIOR CALPHA.
